LIPSTICK BRUSH OR THE LIKE

Louis Sasmor, 4 Askins Place, New Rochelle, N.Y.

Filed July 6, 1964, Ser. No. 80,701

Term of patent 7 years

(Cl. D86—10)

FIG. 1

FIG. 2

FIG. 4

FIG. 5

FIG. 6

FIG. 3

FIG. 1 is a top plan view of a lipstick brush showing my new design in closed locked position;

FIG. 2 is a front elevational view of the lipstick brush in the closed locked position of FIG. 1;

FIG. 3 is a bottom plan view of the lipstick brush;

FIG. 4 is a left side elevational view of the lipstick brush in the closed locked position of FIG. 1, the right side view being the same;

FIG. 5 is a view similar to FIG. 4, but illustrating the lipstick brush in an open unlocked position with the locking sleeve lowered and the brush applicator swung out; and

FIG. 6 is a front elevational view of the lipstick brush in open locked position with the locking sleeve raised and the brush applicator swung out.

I claim:

The ornamental design for a lipstick brush or the like, substantially as shown and described.
